UNITED STATES PATENT OFFICE

154,491

DESIGN FOR A LADY'S HANDBAG

Max Kaplan, Bronx, N. Y.

Application January 13, 1949, Serial No. 219

Term of patent 14 years

(Cl. D87—3)

To all whom it may concern:

Be it known that I, Max Kaplan, a citizen of the United States and a resident of Bronx, New York, in the county of Bronx and State of New York, have invented a new, original, and ornamental Design for a Lady's Handbag, of which the following is a specification, reference being had to the accompanying drawing, forming a part thereof, wherein:

Fig. 1 is a perspective view of a lady's handbag showing my new design;

Fig. 2 is a front elevational view thereof;

Fig. 3 is an end elevational view thereof; and
Fig. 4 is a plan view thereof.

The dominant feature of my design for a lady's handbag resides in the rigid spaced collateral bars at the top of the handbag, said feature being shown in full lines.

I claim:

The ornamental design for a lady's handbag, substantially as shown and described.

MAX KAPLAN.
